ATTORNEY

UNITED STATES PATENT OFFICE.

JOHN D. STEWART, OF BALTIMORE, MARYLAND.

IMPROVEMENT IN LETTER-BOXES.

Specification forming part of Letters Patent No. **147,445**, dated February 10, 1874; application filed January 2, 1874.

To all whom it may concern:

Be it known that I, JOHN D. STEWART, of Baltimore city, in the county of Baltimore and State of Maryland, have invented certain new and useful Improvements in Letter-Boxes; and I do hereby declare that the following is a full, clear, and exact description thereof, reference being had to the accompanying drawings and to the letters of reference marked thereon, which form a part of this specification.

My invention relates to letter-boxes having an interior rocking-plate operated by the raising of the lid or cover for the aperture through which the letters are admitted; and the nature of my invention consists in the construction of said lid or cover with a projection on each side for pivoting the same within the letter-box, and with an arm at each side to operate the rocking-plate, as will be hereinafter more fully set forth.

Figure 1 represents a vertical section, showing an end view of the tilting platform and lid or cover; and Fig. 2 is a reduced front elevation.

In order to enable others skilled in the art to which my invention appertains to make and use the same, I will now proceed to describe its construction and operation, referring to the annexed drawing, which represents a transverse vertical section of a letter-box embodying my invention.

A represents a letter-box of any suitable construction, provided on one side with an aperture, *a*, through which the letters or other mail matter is to be admitted. Within the box *A*, opposite to the aperture *a*, is a stationary inclined board, *B*, extending entirely across the box from the top downward for a suitable distance. *C* represents the rocking plate, which also extends entirely across the box, and is hung between the aperture *a* and the board *B* in such a manner that when the lid or cover for said aperture is raised to admit letters, the plate will extend from below the aperture to the lower end of the board *B*, and thereby effectually prevent any instrument from being inserted to abstract any mail matter from the box.

Rocking plates having been used before for

this purpose, I do not, broadly, claim such as my invention.

D represents the lid or cover for the letter-aperture *a*, the upper portion of the same being curved, as shown, and at each side a curved arm, *b*, extends inward and downward from the same. The upper edge of this arm forms, with the exterior surface of the curved part of the lid, nearly a true semicircle, and an ear or projection, *d*, extends downward from the same.

The main part of the lid or cover *D* is passed through a slot or aperture, *x*, above the letter-aperture *a*, from the inside of the box outward, and the lid is then pivoted to the inside of the box through the ends of the ears or projections *d d*, the pivot-point being the center of the semicircle above described. The arms *b b* form stops for the upward movement of the front end of the plate *C*, the rear edge of said plate being the heaviest, so as to throw the front end upward.

Now, when the lid *D* is raised, it passes partially into the interior of the box, and the arms *b b* force the rocking plate *C* into the position shown by the dotted line in the drawing. Letters may now be admitted through the opening *a*, between the arms *b b*, onto the plate *C*, and as soon as the lid *D* is lowered the plate *C* turns and deposits the letters on the bottom of the box *A*.

Having thus fully described my invention, what I claim as new, and desire to secure by Letters Patent, is—

1. The lid or cover *D*, constructed as described, with an arm, *b*, and an ear or projection, *d*, at each side, and pivoted within the box *A*, the main part of the lid passing through an aperture, *x*, in the manner substantially as herein set forth.

2. The combination of the box *A* with openings *a x*, rocking plate *C*, and the lid *D*, provided with arm *b* and projection *d* at each end, all constructed substantially as and for the purposes herein set forth.

In testimony that I claim the foregoing as my own I affix my signature in presence of two witnesses.

Witnesses: JNO. D. STEWART.
